CLAIM

The ornamental design for a portion of a cleaning sheet, as shown and described.

DESCRIPTION

FIG. 1 is a perspective view of the portion of a cleaning sheet, embodying the new design;

FIG. 2 is a top view thereof;

FIG. 3 is a front view thereof, the opposite back view is the mirror image thereto; and,

FIG. 4 is a side elevation view thereof, the opposite side is a mirror image thereto.

The broken lines shown in the drawings are for illustrative purposes only and form no part of the claimed design.
